UNITED STATES PATENT OFFICE.

ALBERT E. PEAKE, OF EVERETT, WASHINGTON.

MEANS FOR DISPLAYING PICTURES AND THE LIKE.

No. 811,432.

Specification of Letters Patent.

Patented Jan. 30, 1906.

Application filed March 13, 1905. Serial No. 249,948.

To all whom it may concern:

Be it known that I, ALBERT E. PEAKE, a citizen of the United States, residing at Everett, in the county of Snohomish and State of Washington, have invented certain new and useful Improvements in Means for Displaying Pictures and the Like, of which the following is a specification.

My invention relates to improvements in means for displaying pictures and the like; and the primary object thereof is to provide a hermetically-sealed incasement in which the picture is arranged.

Further objects and advantages will be set forth in the following description and those features of construction on which I base my claim for protection defined in the appended claims.

In the accompanying drawings, in which like numerals of reference indicate like parts throughout the several views, Figure 1 is a view in perspective of a tombstone provided with my improvement. Fig. 2 is a fragmentary sectional view thereof. Fig. 3 shows another application of my improvement, and Fig. 4 shows the incasement in position to receive the photograph and binding-cement.

In carrying out my invention I provide a transparent incasement which preferably consists of two transparent sections 1 in the form of flat rectangular plates, the same having their edges grooved to provide inner and outer ribs 2 and 3, said grooves being of such cross-sectional contour as to provide concave pockets, as 4, in the adjacent sides of the ribs. The inner ribs of the respective sections abut each other and are of less height than the outer ribs. Consequently when the cementitious composition is placed in the grooves and firmly compressed therein, so as to have its outer face lie flush with the outer edges of the ribs 3, it will extend over the outer faces of ribs 2, and thereby bind the two sections 1 firmly together.

The picture (indicated at 6) is placed between the two sections 1. Then the cementitious binder is inserted in the grooves of the sections and forced into the pockets of ribs 2 and 3. This obviously enables the binder to take a firmer hold, and accidental dislodgment thereof will be prevented.

In the drawings I have shown for the purposes of illustration the picture 6 inclosed; but it is apparent in lieu of the picture valuable

papers or any other matter which it is desired to be preserved can be substituted, and without departing from the spirit of my invention the incasement, with the matter sealed therein, can be employed in any connection. Two applications are shown in the drawings, one illustrating my improvement secured by cement in a concavity provided in one face of a tombstone 7, and, as will be obvious in this connection, the picture of the deceased party will always be protected from inclement weather and unscrupulous persons. In the other form (shown in Fig. 3) the incasement is shown as being suspended, by means of a flexible connection 8, on a hook attached to a picture-molding 9. The connection 8 has its free ends attached to small eye-bolts embedded in the cementitious composition 5.

By providing an incasement of the character described a simple and inexpensive construction is provided, and the binder 5, extending over the contiguous edges of the respective sections, prevents air or moisture gaining access to the subject incased, and by forming the grooves in the edges of the sections they, aside from assisting in retaining the binder in position, can, if so desired, be suitably colored, so as to produce a border which will give a pleasing effect and serve to set off the picture or other matter displayed in the incasement.

Having thus described my invention, what I claim as new, and desire to secure by Letters Patent of the United States of America, is—

1. An incasement comprising a plurality of sections arranged one on the other and having their edges provided with spaced-apart ribs, and a cementitious binder extending over the adjacent ribs of said sections and into the spaces between the ribs of the respective sections.

2. An incasement comprising a plurality of transparent sections arranged one on the other, said sections being formed with spaced-apart ribs on their edges, the ribs of each section having their inner faces cut out, and a cementitious binder extending over the adjacent ribs of said sections and into the cut-out portions of the ribs of the respective sections.

3. An incasement comprising a plurality of transparent sections arranged one on the other, said sections having their edges pro-

vided with raised portions, and a cementitious binder extending over said raised portions for holding the sections together.

4. An incasement comprising a plurality of 5 transparent sections arranged one on the other, said sections having ribs formed on their edge portions, the adjacent ribs of said sections being of less height than the other ribs, and a cementitious binder extending

over the adjacent ribs of said sections and 10 into the spaces between the ribs of the respective sections.

In testimony whereof I affix my signature in presence of two witnesses.

ALBERT E. PEAKE.

Witnesses:
